UNITED STATES PATENT OFFICE.

HERBERT A. SIMPSON, OF EAST LANSING, MICHIGAN.

COLLAPSIBLE PARTITION.

Application filed November 3, 1924. Serial No. 747,659.

My invention has among its objects to provide means for converting a room into a number of smaller rooms. A further object of my invention is to provide a collapsible partition normally concealed within a hollow cabinet forming a column or recess and adapted to be extended to form a partition. The invention is particularly adapted, though not necessarily limited, for converting a large church room into a number of smaller Sunday school rooms, or for converting a room into one or more booths, etc.

One example of an application of my invention may be formed in connection with churches. A primary requisite in present day Sunday school work is the provision of a large number of individual class rooms for departmental work. Most of the older church buildings and many churches of modern construction have not made provision for this need. My invention has among its objects the provision of a plurality of cabinets designed to represent ornamental columns and adapted to contain a partition which may be extended to divide the room into smaller rooms.

With these and other objects in view, the invention resides in the novel features of construction and combinations and arrangements of parts as more fully hereinafter described and claimed.

Referring to the drawings:

Figure 1 is a perspective view showing my partition extended into operative position;

Figure 2 is a section view through the cabinet, the partition being folded within the same;

Figure 3 is a view corresponding to Figure 2, showing the manner in which the partition is supported in its extended position;

Figure 4 is a view along the line 4-4 of Figure 3, showing in addition the manner of supporting the curtain rods prior to folding the partition within the cabinet;

Figure 5 is a detail sectional view of the panel brace;

Figure 6 is a detail view showing the spring clip for holding the curtains in folded position, and

Figure 7 is a detail view showing one means of supporting one of the curtain rods from a wall or the like.

Referring to the drawings 10 indicates a cabinet or column preferably supported by a base 11 so as to position its rear wall 12

adjacent the wall of a room which is to be partitioned. Instead of so arranging the cabinet I might locate it entirely within the wall forming a recess opening outwardly into the room. The cabinet 10 is provided with a movable panel 13 which is pivotally mounted adjacent one end by pins 14 carried by shoes 15 slidably engaging in longitudinally extending channels 16 in opposite sides of the inner side faces of the cabinet. At the other end the panel is supported within the bottom molding 11'. 17 is a brace comprising the telescoping sections 18 and 19, the former of which is pivotally connected at 20 to the base of the cabinet and the latter of which is similarly pivoted at 21 to the panel 13 intermediate its ends. 22 is a compression coil spring within the sections of brace 17 the spring tending to force section 19 away from section 18, the outward limit being determined as shown in Figure 5 by a spring clip 23 carried by collar 24 which is adjustable by a set screw 25 or the like longitudinally along the section 19. The opposite end of the spring clip 23 carries a projection 26 adapted to engage a suitable recess in the section 18 as the sections slide longitudinally of each other for holding the sections in proper extended position. Movement of the sections of the brace 17 is accompanied by an outward movement of the panel 13 from the position shown in Figure 2 to a horizontal position as shown in Figure 3, shoes 15 sliding in slots 16 to guide the panel in its movement. One of the shoes is preferably provided with a detent 27 adapted to automatically engage a recess 28 in latch 29, the latter being weighted at 30 to normally position the recess 28 in the path of the detent 27. A stop 31 may be provided to limit the movement.

Curtains 32 and 33 are adapted to form partition walls and are carried by rings 34 upon telescopic rods 35 and 36 respectively. The latter rods are suspended from the panel 13 adjacent the pivoted end thereof by means of hooks 37, the rods being suspended at their other end by means of hooks 38 swiveled in the panel 13 whereby either rod may be disengaged from its hook 37 and swiveled upon its hook 38 to direct it at any angle for forming a partition of the room. As shown in Figure 1 rod 36 is positioned at substantially a 90° angle with rod 25 the rod 36 being extended to the desired length, a collapsible tripod stand 39

supporting the free end of rod 36 in a U-shaped bracket 40 carried by stand 39. The legs of the tripod are preferably collapsible so that when not in use the stand may be housed within the cabinet 10.

Preferably when stand 39 is employed as shown in Figure 1 the rod 36 is extended to form a partition greater than the normal length of the rod would provide, where a plurality of adjoining rooms or partitions are desired, the cabinets 10 are spaced within limits defined by the extended length of the rods. In this latter instance, the stands 39 are dispensed with, the extended rods 10 running parallel with the wall adjacent the cabinets, the extended free ends of the rods being supported by the outer ends of the fixed rods of the next panel 13. Thus, the curtain extending longitudinally of the 15 panel 13 forms a partition perpendicularly with the wall, the other curtain of the cabinet extending parallel with the wall to complete the room.

For retaining the curtains in folded position, upon the rods at one end thereof there is a spring clip 41 slidably supported in bracket 45 formed with legs 42 connected by an offset portion 43 with a body portion 44, the latter being at right angles with the 20 legs 42. The clip 41, when the parts are collapsed as in Figure 2, is positioned so as to direct the legs 42 perpendicularly with the panel 13 against the curtains 32 and 33 thereby holding them in place at one end 25 of the curtain rods. After the panel 13 is swung outwardly to the position shown in Figure 3 the clip 41 is swung through an arc of 90° in its bracket 45 until the body portion 44 is perpendicular to the panel 13 and the legs 42 are in contact therewith, then the clip is slid longitudinally of the 30 panel until the offset portions 43 serve to hold the clip, by reason of its resilience, in the position shown in Figures 3 and 6, the rings 34 carrying the curtains are then distributed along the length of the curtain 35 poles.

Referring to Figure 7, I have shown a manner of supporting the free end of one 40 of the rods from a wall 46 instead of the stand 39 as shown in Figure 1. In this construction an eyelet 47 is screwed to the wall 46 and the end of rod 36 (or rod 35) is suspended from the eyelet through a hook 48 having a part 49 extending downwardly and outwardly from the wall so as to engage the curtain rod and hold it spaced from the 45 way sufficiently to accommodate the head 50 of the curtain rod.

In operation with the parts folded within 55 the cabinet as shown in Figure 2, panel 13 is lifted by a suitable handle or as shown in Figure 1, by engaging the fingers in the recess 13' in the face of the panel 13. The 60 panel is thus lifted sufficiently to clear the

bottom molding 11' after which the panel will swing outwardly under the influence of spring 22, until the projection 26 engages the opening in the section 18 to rigidly unite the telescoping sections 18 and 19. As the 65 panel 13 swings outwardly on its pivotal pins 14 the shoes 15 slide downwardly in slots 16 until detent 27 swings latch 29 on its pivot to engage recess 28 as shown in Figure 3. Upward movement of the shoes 70 15 is thus prevented by latch 29. The curtains 32 and 33 are then distributed along the curtain poles. In this position in first 75 assembling the apparatus, should the panel 13 not be horizontally extended the collar 80 24 may be adjusted by set screw 25 longitudinally of the section 19 in order to shorten or lengthen the brace 17. Clip 41 is then 85 swung into the position shown in Figures 3 and 6. One of the curtain rods (or both if desired) is then released from the hook 37 and swung on the swivel hook 38 at any angle to form the desired partition. The 90 free end of the curtain rod is then supported by a stand 39 or from the wall as shown in Figure 7. The stand 39 when not in use may be collapsed and stored within the cabinet 10.

In restoring the parts to the position 95 shown in Figure 2, the operator releases the spring clip 23 and rocks the latch 29 sufficiently to disengage the recess 28 from detent 27. The panel may then be swung toward the cabinet, the lower end of the 100 panel being positioned behind the molding 11'.

It is obvious that by arranging two cabinets opposite each other a curtain of each cabinet can be extended perpendicularly with the wall, the two extended curtains being in alignment and having their extended free ends abutting and supported by a stand such as shown at 39 to form a partition across the room. Thus, the room may 105 be divided into a plurality of 110 rooms by transverse partitions.

If desired any one cabinet may be arranged to form a room by partitioning off a corner of a room by extending one of the 115 curtains at an angle of 90° with the extended panel 13, the free end of the extended rod being supported by a stand 39 or from the wall by the device shown in Figure 7, preferably the latter.

The cabinets also provide space for the 120 storing of class supplies such as books, papers, maps, etc. This feature is of considerable value to teachers in avoiding loss of such papers and confusion incident to their misplacement.

The cabinet may be designed to represent 125 an ornamental or structural column fitted snugly against the ceiling thus adding to the attractiveness of the room.

While it is believed that from the fore- 130

going description, the nature and advantages of my invention will be readily understood, I desire to have it understood that I do not limit myself to what is herein shown and described and that such changes may be resorted to when desired as fall within the scope of the claims.

What I claim as my invention is:—

1. A partition comprising a cabinet having a panel movable outwardly therefrom, a brace having its opposite ends fastened to the panel and cabinet respectively, a pair of curtain poles supported adjacent the panel, and curtains supported by said poles to form partition walls, one of said curtain rods having a swivel connection at its outer end for positioning its curtain at an angle with the other said curtain rod.

2. A partition comprising a cabinet having a panel movable outwardly therefrom, a brace having its opposite ends fastened to the panel and cabinet respectively, a pair of curtain poles supported adjacent the panel, and curtain supported by said poles to form partition walls, one of said curtain rods having a swivel connection at its outer end for positioning its curtain at an angle with the other said curtain rod, and means for supporting the free end of the said swiveled curtain rod.

3. A partition comprising a cabinet having a panel movable outwardly therefrom, a brace having its opposite ends fastened to the panel and cabinet respectively, a pair of curtain poles supported adjacent the panel, and curtains supported by said poles to form partition walls, one of said curtain rods having a swivel connection at its outer end for positioning its curtain at an angle with the other said curtain rod, and means for supporting the free end of the said swiveled curtain rod, said curtain rods, curtain and brace adapted to fold within the cabinet when not in use.

4. A partition comprising a cabinet provided with a movable panel normally positioned longitudinally of the cabinet and forming a front closure therefor, said panel having a pivotal sliding movement at one end with said cabinet permitting said panel to be extended outwardly from the cabinet, said panel in its outward position being pivoted adjacent the upper end of the cabinet, means for bracing the panel in the latter position, and a curtain carried by said panel and foldable within the cabinet for forming a partition wall when the panel is moved outwardly from the cabinet.

5. A partition comprising a cabinet provided with a panel having a sliding pivotal engagement at one end thereof with said cabinet whereby said panel may be extended outwardly from said cabinet, said panel in its outward position being pivoted adjacent the upper end of the cabinet, a telescoping

brace for guiding the outward movement of the panel and for supporting said panel in its extended position, and means for supporting a partition wall by said panel.

6. A partition comprising a cabinet provided with a panel having a sliding pivotal engagement at one end thereof with said cabinet whereby said panel may be extended outwardly from said cabinet, a telescoping brace for supporting said panel in its extended position, and means for supporting a partition wall by said panel, the support for one of said walls permitting its adjustment at an angle with the other of said walls.

7. A collapsible partition for converting a room into a number of smaller rooms comprising a fixed open front member, a panel adapted to form a closure for said opening, said panel being pivoted to extend outwardly from the cabinet adjacent the upper end thereof and provided with means forming partition walls for converting a room into smaller rooms suitable for classroom purposes and means for supporting said panel in its extended position.

8. A collapsible partition comprising a cabinet having an open front and a panel forming a closure for said front and movable outwardly therefrom, said panel in its outward position being pivoted adjacent the upper end of the cabinet, a brace having its opposite ends fastened to the panel and cabinet respectively for guiding the outward movement of the panel, said brace being located within the cabinet at times, and means associated with the panel and carried thereby in its extended position forming a partition wall for converting a room into smaller rooms suitable for classroom purposes.

9. A collapsible partition comprising a cabinet having a panel movable outwardly therefrom, said panel in its outward position being pivoted adjacent the upper end of the cabinet, a brace having its opposite ends fastened to the panel and cabinet respectively, a pair of curtain poles supported adjacent the panel and adapted to lie within the cabinet in the folded position of the panel and curtains supported by said poles to form partition walls for converting a room into smaller rooms suitable for classroom purposes when said panel is moved outwardly from the cabinet.

10. A collapsible partition comprising a cabinet formed with an open front and provided with a movable panel normally positioned longitudinally of the cabinet to form a closure for said opening, said panel having a pivotal sliding movement at one end with said cabinet, permitting said panel to be extended outwardly from the cabinet adjacent the upper end thereof, means for bracing the panel in the latter position, and a

curtain carried by the panel for converting a room into smaller rooms suitable for classroom purposes for forming a partition in the extended position of the panel.

5. 11. A collapsible partition comprising a cabinet formed with a panel, shoes pivoted to the panel, said cabinet having grooves adapted to slidably receive said shoes permitting said panel to move downwardly and outwardly from said cabinet, said panel in its outward position being pivoted adjacent the upper end of the cabinet, means for bracing said panel in its outward position comprising a telescoping brace, a coil spring within 10 said brace assisting the outward movement of the panel, means for positively holding the telescopic sections in extended position, a latch for holding the panel in its extended position and partition walls associated with 15 said panel in its extended position for converting a room into smaller rooms suitable for classroom purposes.

12. A cabinet comprising longitudinally extending grooves, a panel having pivotal 20 sliding connection in said grooves and a 25

telescopic brace secured at its opposite ends to the panel and cabinet respectively, said panel in its outward position being pivoted adjacent the upper end of the cabinet, a curtain carried by the panel, and means associated with the brace tending to move the panel for positioning the curtain to form a partition for converting a room into smaller rooms suitable for class room purposes. 30

13. A collapsible partition for converting a room into smaller rooms comprising a cabinet having a panel movable outwardly therefrom, a brace having its opposite ends fastened to the panel and cabinet respectively, a pair of curtain poles supported adjacent 35 the panel and adapted to lie within the cabinet in the folded position of the panel, curtains supported by said poles to form partition walls when said panel is moved outwardly from the cabinet, and means for securing the curtains at one end of the curtain poles when the panel is in its folded position. 40

In testimony whereof I affix my signature.

HERBERT A. SIMPSON.
